UNITED STATES PATENT OFFICE.

ERIE A. WITHERELL, OF GALESBURG, ILLINOIS, ASSIGNOR TO HERMAN E. DICK, OF SAME PLACE.

MAGNETO-ELECTRIC MACHINE.

SPECIFICATION forming part of Letters Patent No. 223,623, dated January 13, 1880.

Application filed August 16, 1879.

To all whom it may concern:

Be it known that I, ERIE A. WITHERELL, of Galesburg, in the county of Knox and State of Illinois, have invented certain new and useful Improvements in Magneto-Electric Machines; and I do hereby declare that the following is a full, clear, and exact description of the invention, which will enable others skilled in the art to which it appertains to make and use the same, reference being had to the accompanying drawings, and to letters of reference marked thereon, which form a part of this specification, in which—

Figure 1 is a perspective view of my invention inclosed in a pocket-case. Fig. 2 is a perspective view, showing the case open. Fig. 3 is a sectional view in the line *x x* in Fig. 5. Fig. 4 is a sectional view in the line *y y* in Fig. 3. Fig. 5 is a sectional view in the line *z z* in Fig. 3. Fig. 6 is a sectional view in the line 2 2 in Fig. 3. Fig. 7 is a side elevation, showing the machine in favorable position for operation.

This invention relates to magneto-electric machines of that class in which electric currents are induced by an armature encircled by a wire coil and moving in the magnetic field of a magnet, and more particularly to that class of such machines adapted by compactness of form for medical uses.

The object of this invention is to produce a machine of comparatively great electro-motive force with the greatest possible compactness of form, the whole machine being included 35 within or between the arms or limbs of the magnet.

The invention consists, first, in combining with a horseshoe-magnet an armature formed of a bundle of soft-iron wires, encircled by a 40 wire coil wound transversely round a bundle of wires in the manner hereinafter to be described; second, in an armature arranged to revolve between the poles of a horseshoe-magnet and in a plane cutting both ends of the 45 magnet transversely.

The invention further relates to construction and combination of parts hereinafter described, and set forth in the claims hereto annexed.

50 Referring to the drawings by letters, A rep-

resents an ordinary horseshoe-magnet, with a plate of wood or other non-conductor, B, fixed between the limbs *a a* of the magnet, and extending from its bend *a'* to within a short distance of the poles, or in any other convenient 55 location, to form bearings for the operating parts, as hereinafter described.

C is a shaft, its lower end, *c*, stepped in the bend *a'* of the magnet for a bearing, and its upper portion surrounded by a sleeve, D, between which and the shaft C is placed an insulator, *d*. The sleeve D and shaft C rotate together, their upper ends in bearing-plates E, which are secured to the plate B at their ends, and have their central part in constant 65 contact with the sleeve D, as shown at Fig. 5 of the drawings. The shaft C is held from longitudinal movement by a pin, *c'*, which projects from the plate B above a collar, *c''*, on said shaft.

F is a bundle of soft-iron wires, placed parallel with each other in a spool, G, of wood or other suitable material, around which spool the ordinary insulated wire H is wound. I is a case of brass or other conducting material, 75 partially surrounding the wire coil H, as shown at Fig. 4 of the drawings.

A paper wrapping may be placed between the coil H and casing I for greater protection of the coil.

The case I is secured to the upper end of the sleeve D, so as to be rotated with said sleeve, and one end, *h*, of the wire coil H is in contact with the case I, and thus in connected line with the sleeve D. The other end, *h'*, of 85 the wire coil is in contact with the upper end of the shaft C, which is insulated from the case I. (See Fig. 3 of the drawings.)

The wires F are at right angles to the shaft C, and are located, preferably, with their central longitudinal line in a line which connects the poles of the magnet.

J is a circuit-breaker, formed of a spring-plate secured at its midlength portion to the plate B, and its outer end in contact with one 95 of the limbs *a* of the magnet. The inner end of the spring-plate J extends across the sleeve D, which is flattened on its two opposite sides, which are parallel with the bundle of wires F, as shown at Fig. 6 of the drawings, and so that 100

in rotating the sleeve D its flat sides will not touch the spring-plate J, but its extended sides, will bear against it.

K K' are ordinary conducting-wires secured 5 to the central part of plugs k k', one of which, k, may be inserted in a socket in the plate B to bring it in contact with the bearing-plates E, and the other, k', inserted in a socket in same plate to bring it in contact with the circuit-breaker J.

L is a collar, of rubber or other suitable material, secured upon the sleeve D, and gears by frictional contact with the face of a wheel, M, which is provided with an annular ring, m, of 15 rubber or other suitable material, and may be rotated by a crank, m', to impart rotary movement to the shaft C, sleeve D, and armature F.

P is a case inclosing the apparatus, and is formed of a part, P', which incloses all of the 20 magnet except the projecting ends where the armature rotates. One side, P'', of this portion of the case is secured to the magnet, and the other side, P''', is hinged thereto, so that it may be turned back, as shown at Fig. 2 of 25 the drawings, for access to the actuating devices. The shaft m' of the wheel M is journaled in the part P''' of the case, and hence is turned back with the part P''' in opening it, as shown at last figure named. An end cap, 30 Q, completes the inclosing-case and holds the part P''' in a closed position when in place.

In operation, the cap Q is removed, and as a 35 convenient position for the machine it may be placed with one end resting and supported on and by the plugs K K', as shown at Fig. 7 of the drawings. The part P''' of the case being closed, turning the crank m' will rotate the armature F, bringing each of its ends alternately to the north and south poles of the 40 magnet, and thus successively magnetizing it in opposite directions, and thus inducing two opposite currents in the wire coil at each complete revolution of the armature.

The construction of the armature of a bundle 45 of wires such as described greatly increases its efficiency and rotation in the position and manner described, will greatly facilitate the rapid change of magnetization and change of direction of current, and so nearly 50 overcome the coercive force of the armature

that great speed may be given without danger of increasing the speed beyond that at which the greatest change of magnetization occurs. In addition to diminishing its coercive force by the rotation of the armature, as 55 described, its rotation in the manner described and in the most intense part of the field of the magnet will greatly increase the current induced.

The operation of the circuit-breaker J in reversing and rendering the currents intermittent will be obvious.

Locating all the operating parts between the limbs of the magnet gives great compactness to the machine, and thus specially adapts 65 it for medical use.

What I claim as new, and desire to secure by Letters Patent, is—

1. In a magneto-electric machine, an armature and wire coil, as described, provided with 70 the rotating device passing through bearings E attached to non-conducting plates B, and a circuit-breaker, J, all located within the limbs of a horseshoe-magnet, substantially as described.

2. In a magneto-electric machine, an armature and wire coil, as described, with the rotating mechanism located between the limbs of a horseshoe-magnet and inclosed by a case 80 having one side secured to the magnet and the other side hinged thereto, substantially as described, and for the purpose set forth.

3. In combination with the horseshoe-magnet, an armature formed of a bundle of straight wires and an encircling coil of wire encircled 85 by a case, I, sleeve D, shaft C, circuit-breaker J, and bearings E, substantially as described, and for the purpose specified.

4. In combination with the horseshoe-magnet, armature, wire coil, case I, sleeve D, shaft 90 C, circuit-breaker J, and bearings E, the friction-wheels M and L, substantially as and for the purpose specified.

In testimony that I claim the foregoing as my own I affix my signature in presence of 95 two witnesses.

ERIE A. WITHERELL.
